UNITED STATES PATENT OFFICE.

SOPHIE MOSKOVITZ AND PHILIP MOSKOVITZ, OF PHILADELPHIA, PENNSYLVANIA.

COMBINATION HAIR WAVER.

Application filed October 20, 1925. Serial No. 63,765.

Our invention relates to a new and useful improvement in hair curlers and particularly to the type of hair curler which is adapted to produce the curled or waved effect in the hair, by retaining the hair properly crimped and clamped for a relatively great length of time and without the application of any heat.

Our invention relates more particularly to a hair curler of the character stated, comprising two or more pairs of resilient metal arms, bowed or curved in longitudinal cross section and curved or channelled in transverse cross section; the arms of each pair being hingedly or otherwise connected at one of their ends and having clasping means at their other ends to secure or lock the same in closed position and one of the arms of each pair being also rigidly connected to each other in parallel spaced relation, by a suitable interconnecting member or web. Our invention also relates to an auxiliary curling device consisting of a pair of similarly bowed arms, also connected at one of their ends and being provided with suitable clasping means at their other ends; said auxiliary curling device being adapted to clamp the hair in a flat condition between two pairs of parallel spaced curved or channelled clamping devices, so as to produce a relatively straight portion intermediate of each two waves or curls in the hair.

For the purpose of illustrating our invention, we have shown in the accompanying drawings forms thereof which are at present preferred by us, since they will give in practice satisfactory and reliable results, although it is to be understood that the various instrumentalities of which our invention consists can be variously arranged and organized and that our invention is not limited to the precise arrangement and organization of these instrumentalities as herein shown and described.

Referring to the drawings,

Figure 1 represents a perspective view of a hair curler embodying our invention shown in the opened position.

Figure 2 represents a similar perspective view of the same in the closed position thereof.

Figure 3 represents a perspective view of the auxiliary curling device in the opened position.

Figure 4 represents a section on line 4-4 of Figure 3, showing the transverse curva-

ture of the bowed arms, shown in Figures 1 and 2.

Referring to the drawings in which like reference characters indicate like parts, 1 and 2 and 3 and 4, designate pairs of longitudinally bowed or curved arms or clamping members. The pair of arms 1 and 2 are connected at one of their ends by the hinged connection 5, or any other suitable means, 60 while the other pair of arms 3 and 4 are similarly connected at their corresponding ends by a corresponding hinge 6, or the like.

A connecting member or web 7 is formed integral with one of the arms (1 and 3) of each pair of arms, at their hinged or connected ends, and rigidly unites and interconnects such arms 1 and 3 in spaced and parallel relation to each other, as shown in Figures 1, 2 and 4.

As shown in Figure 3, each of the arms 1 and 2, and 3 and 4, is curved in transverse cross section, the curvature of the arms of each coacting pair being in the same direction, so as to conform to each other and fit 80 within each other snugly when in the closed position, as shown in Figures 2 and 4.

The arms 1 and 2, and 3 and 4, are made of suitable resilient sheet metal, of suitable thickness; the length of the arms being sufficient to extend from the temples to the back of the head on either side of the head. The longitudinal curvature or bow shape is such as to conform to the shape of the head and to fit snugly around the same.

Each of the arms 2 and 4 is provided with corresponding clasp members 8 and 9 respectively, which are adapted to slide over the terminals 10 and 11 respectively of the arms 1 and 3 by a slight lateral movement, 95 thus to engage said terminals and thereby to lock said pairs of coacting arms in the closed position shown in Figure 2 and 4.

The hair curler of our invention, shown particularly in the figures, is applied to the 100 hair without any heat, and is merely opened and positioned around the head with the tress of hair disposed between the hinged arms 1 and 2, and 3 and 4, whereupon said arms are closed and locked in the position 105 shown in Figure 2. By this means a pair of parallel and spaced curls or waves are produced, to the full extent of the length of the arms 1 and 2, and 3 and 4, and extending entirely across the side of the head.

In order further to accentuate the parallel spaced curls or waves thus produced, we may

provide an auxiliary curling device 13, shown in Figure 3, comprising a pair of flat arms 14 and 15 of slightly lesser length than the length of the arms 1, 2, 3, and 4, and similarly bowed or curved longitudinally however, and of a width slightly less than the space 12 between the arms 1 and 3, (see Figure 1). The arms 14 and 15 are also of resilient sheet metal and may either be hingedly connected at one end, or may be integrally connected as at 16. One of the arms 15, is also provided with a clasp 17, similar to the clasps 8 and 9. The auxiliary waving or curling device 13 is then inserted in the space 12, between the arms 1 and 3, embracing the hair between said arms, and clamping the same in a flat condition.

When the curler is thus applied for a sufficient length of time and then removed from the hair the parallel curls or waves produced by the transversely curved or channeled arms 1 and 2, and 3 and 4, will be separated by a straight portion, which will not only accentuate the waves but will also produce a pleasing effect, by the combination of such alternating straight and waved hair portions.

It will now be apparent that we have devised a new and useful combined hair waver which embodies the features of advantage enumerated as desirable in the statement of the invention and the above description and while we have in the present instance shown and described a preferred embodiment thereof which will give in practice satisfactory and reliable results, it is to be understood that such embodiment is susceptible of modification in various particulars without de-

parting from the spirit or scope of the invention or sacrificing any of its advantages.

Having thus described our invention, what we claim as new and desire to secure by Letters Patent is:—

1. In a device of the character stated, a plurality of pairs of resilient sheet metal arms, each being bowed longitudinally and being curved in transverse cross section; the arms of each pair having one of their ends connected, clasping means common to the free ends of each pair, and integral connecting web rigidly and fixedly interconnecting the connected ends of one arm of each of said plurality of pairs, in spaced and substantially parallel relation to each other. 45

2. In a device of the character stated, the combination of a main curling device comprising a plurality of pairs of resilient arms, each being bowed longitudinally and being curved in transverse cross section; the arms of each pair having one of their ends connected clasping means common to the free ends of each pair and an integral connecting member rigidly and fixedly interconnecting the connected ends of one arm of each of said plurality of pairs, in spaced and substantially parallel relation to each other, 55 60 65 with an auxiliary curling device comprising a pair of flat and bowed resilient arms connected at one of their ends and having clasping means common to their ends, adapted to be inserted between the spaced pairs of arms 70 of said main curling device.

SOPHIE MOSKOVITZ.
PHILIP MOSKOVITZ.
